UNITED STATES PATENT OFFICE

118,743

DESIGN FOR AN INSECT TRAP OR THE LIKE

Candido Nicolini, Solvay, N. Y.

Application November 16, 1939, Serial No. 88,324

Term of patent 14 years

To all whom it may concern:

Be it known that I, Candido Nicolini, a citizen of the United States, residing at Solvay, in the county of Onondaga and State of New York, have invented a new, original, and ornamental Design for an Insect Trap or the like, of which the following is a specification, reference being had to the accompanying drawing, forming part thereof.

Figure 1 is a top plan view of an insect trap or the like showing my new design.

Figure 2 is a side elevational view thereof.

Figure 3 is a transverse vertical sectional view taken through Figure 1 approximately on the line 3—3 and looking upwardly in the direction of the arrows.

I claim:

The ornamental design for an insect trap or the like, as shown.

CANDIDO NICOLINI.
